UNITED STATES PATENT OFFICE

EDWARD J. PAQUE, OF CINCINNATI, OHIO, ASSIGNOR TO THE POLLAK STEEL COMPANY,
OF CINCINNATI, OHIO, A CORPORATION OF OHIO

WINGED CHANNEL POST AND CLIP

Application filed February 23, 1932. Serial No. 594,536.

This invention relates to improvements in metal fence posts, and has for its object to provide a channel-shaped fence post, a cross section of which is U-shaped with laterally 5 extending flanges.

It is particularly the object of this invention to provide a channel-shaped fence post with holes in the sides thereof for receiving 10 clips by which strands of wire may be supported on the post.

It is also an object of this invention to provide a post composed of a minimum amount of material and having a maximum amount of bearing surface by which the post 15 may be securely held in the earth, and also with means provided thereon for securely holding strands of wire in a definite fixed position with relation to the post.

These and other advantages will appear 20 from the following description taken in connection with the drawing.

Referring to the drawing:

Figure 1 is a transverse section showing 25 a full size post with holes therein for receiving wire-holding clips.

Figure 2 is a top plan view of one of the 30 clips.

Figure 3 is an end view of the clip shown in Figure 2.

Figure 4 is a section similar to Figure 1, 35 showing the clip supporting a strand of wire on the post with one end of the clip unlooped around a strand of wire.

Figure 5 is a view similar to Figure 4 but with both ends of the clip looped around a 40 strand of wire.

This invention relates to U-shaped posts, the closed part of which is indicated by the 45 numeral 1 and is called the back part of the post. To each edge of the back part of the post is attached a side 2, which terminates in a flange 3. There are two of these flanges, one on each side, and they are in alignment with each other to provide bearing surfaces 50 for strands of wire to be supported on the post.

Suitably provided in the sides of the post 55 are holes 7. The holes are arranged in pairs, one in each side, to receive a clip 8, such as that shown in Figures 2 and 3, for supporting

strands of wire on the flanges. The clip has on each end a loop 9, which extends around a strand of wire 10 for holding the wire against the flanges on one side of the post, as shown in Figures 4 and 5. In Figure 4 only 55 one end of the clip is looped around the strand of wire. The other end merely engages a flange on one side of the post.

In Figure 5 both ends of the clip are shown looped around the strand of wire. These 60 looped parts are on opposite sides of the post adjacent the flanges. The flanges prevent the longitudinal movement of the clip and the clip prevents the vertical movement of the 65 strands of wire on the post. The holes 7 may be arranged at various points along the length of the post so that the strands of wire may be supported thereon and the space between the strands regulated to suit the needs 70 and conveniences.

By means of the post here provided the strands of wire may be easily and readily attached to the post, and when attached are securely held by means of the clips. When it 75 becomes desirable to remove the strands of wire from the post the clips may be cut or the loops on the ends broken or bent.

I desire to comprehend within my invention such modifications as may be embraced 80 within my claims and the scope of my invention.

Having thus fully described my invention, what I claim as new and desire to secure by Letters Patent, is:

1. In a post structure for supporting 85 strands of wire, a post formed of a strip of metal and having a back part, sides and flanges extending from the sides, said sides having aligned holes therein, and clip means in the holes for supporting the strands of 90 wire against the flanges, said clips engaging the sides of the post by passing through the holes in said side portions and also engaging portions of the flanges of the post, and adapted to hold a wire against portions of said 95 flanges.

2. In a post structure for supporting 100 strands of wire, a post formed of a strip of metal and having a back part, sides and flanges on the sides, said sides having holes

therein, and wire clips in the holes with their ends looped around the strands of wire, said looped ends contacting side portions of said flanges to hold the wire strands in parallel relation to portions of the flanges.

3. A post provided with side portions and laterally extending flanges extending from said side portions, said side portions having holes, clips passing through said holes, said clips having means for supporting wires in line with said flanges.

In testimony whereof, I affix my signature.
EDWARD J. PAQUE.
